UNITED STATES PATENT OFFICE.

WENZEL LEINERT, OF NEW YORK, N. Y.

BEARING.

1,366,089.

Specification of Letters Patent. Patented Jan. 18, 1921.

Application filed October 30, 1919. Serial No. 334,408.

To all whom it may concern:

Be it known that I, WENZEL LEINERT, a citizen of Russia, and a resident of New York, county of New York, and State of New York, have invented certain new and useful Improvements in Bearings, of which the following is a specification.

This invention relates to an improved bearing for supporting receptacles or other elements that are adapted to be partially rotating, as in tilting bodies, and is adapted to relieve the support and the supported element of shocks incidental to the stopping of the tilting or partial rotation.

In order to fully and clearly illustrate one construction in which this device is used, I will describe and illustrate its use in connection with a tilting tank, such as is fully set forth in my Patent No. 1,319,478, issued Oct. 21, 1919, it having been previously the custom to mount the tanks on the supports by means of knife edges. In tilting from a horizontal to an angular position, especially in large tanks where heavy weights have to be handled, the center of gravity moves from a position vertically relative to the supporting point to one inclined thereto, and the angular resistance is tangential to the arc described by the center of gravity.

The components of such tangential force and resistance are vertical and horizontal, the vertical one being taken care of by a suitable bumper or spring, but the horizontal one has heretofore not been compensated for, which results in a tendency to horizontal movement at the pivot, which is unsatisfactory and which subjects the construction to considerable strain. To overcome this I have devised the present bearing, which permits a limited horizontal movement which is yieldingly resisted and which so cushions the stopping of the tilting movement that there is no excessive strain put on any part of the structure.

It will be understood that the device can be used in other forms of receptacles and supports, and it will come within the scope of this invention to apply this device to such situations or devices as will permit of its use.

The invention is illustrated in the accompanying drawing, in which Figure 1 is a side view of a tilting tank provided with my improved bearing. Fig. 2 is an enlarged face view of the bearing, the left half por-

tion thereof being shown in section. Fig. 3 is a vertical section taken through the center of Fig. 2, and Fig. 4 is a view similar to Fig. 3, showing a modified form of structure.

In the drawing, 10 is a tank representing the supported element, and the tank is adapted to tilt on the support 11, and the tilting, both forward and backward, from and to a horizontal position is of a nature to cause shock to the support and the tank, especially at the bearing.

In the case of large tanks the contents, such as water, makes the tank very heavy and the bearing is subject to considerable displacement when the tilting is stopped. In measuring tanks the journal or bearing must be freely rotatable in order to insure accuracy, such as when the tilting tank is a meter. The center of gravity of the tank will be assured as at *a* when the tank is horizontal, and as at *b* when the tank completes its forward movement; then the force *c* is tangential to the arc *d* described by the path of the center of gravity. An angular resistance perpendicular to the force *c* is impractical, as with different weights or materials to be used in the tank, the location of the center of gravity varies. It thus becomes necessary to take care of the vertical component *e* and the horizontal component *f*.

The bumper 12 and the bolt 13, actuated by the spring 14, are illustrations of means employed to compensate for and cushion the vertical component *e*. To cushion the horizontal component *f* is the function of the present invention, and it consists of a journal or bearing 15, which is constructed so as to yieldingly resist horizontal movement, but is fixed against vertical movement, especially downward.

One form of bearing is illustrated in Figs. 2 and 3. The frame 16 is secured to the top of the support 11 and a casing 17 of the bearing rests on the floor of the frame, usually on a smooth insert 18, which permits the casing 17 to roll thereon. The casing encloses any desired form of anti-friction bearing, such as a ball bearing 19, which receives the shaft 20 of the tank 10.

To yieldingly resist the rolling motion of the journal 17, in other words, to cushion the horizontal movement, I prefer to arrange springs which act to perform this function. One form comprises a bolt 21

which is slidable in the frame 16, and a spring 22 embraces the bolt and abuts at one end on the frame and at the other end on a nut 23, which is screwed on the bolt 21 and thus acts to adjust the tension of the spring 22. A sleeve 24 can be placed over the bolt and thus limits the movement of the yielding resistance by reason of the bolt 23 abutting against the end of the sleeve.

10 The right hand side of Fig. 2 shows a slight modification for the compensation of the rearward action of the bearing, the bolt 25 having a collar 26 to limit its forward movement, having a nut 27 for tensioning 15 the spring 28 and having a shoulder 29 which engages with the side of the frame 16 to limit the movement of the bolt 25. To prevent lateral movement of the casing I prefer to provide the floor plate 18 with a 20 flange 30 which insures the journal 17 rolling straight.

In Fig. 4 I illustrate a modified form in which the front 31 of the frame is provided with a bolt 32 which is screw-threaded into 25 the frame, and the end of the bolt engages the end of the shaft 20 and is preferably locked in position by a lock nut 33. This is a modified construction for preventing lateral movement of the shaft 20, and consequently of the journal 17, as will be evident.

The bolt 21 is usually arranged so that it normally is just out of contact with the

journal, this permitting a free operation of the device in that the journal has a very short initial start of its rolling motion, 35 which is advantageous in finely balanced devices, such as meters, on which the bearing is used.

I claim:

1. A bearing comprising a rotatable shaft, 40 a journal for the shaft, a support on which the journal can roll, a bolt to engage the journal, and a spring for resisting movement of the bolt.

2. A bearing comprising a rotatable shaft, 45 a journal for the shaft, a support on which the journal can roll, a bolt to engage the journal, a spring for resisting movement of the bolt, and means for adjusting the tension of the spring. 50

3. A bearing comprising a fixed support, an insert on said support, the insert having a smooth top surface, a shaft, a journal in which the shaft is mounted, the journal rolling freely on the insert, means for preventing outward endwise movement of the journal, and a spring disposed so as to be engaged by the journal after it moves and normally out of operative contact therewith. 55

In testimony that I claim the foregoing, 60 I have hereto set my hand, this 28th day of October, 1919.

WENZEL LEINERT.
